CARBURETOR

Charles A. Rosier, New York, N. Y.

Application June 14, 1933, Serial No. 675,653

9 Claims. (Cl. 261—50)

Ths invention relates to carburetors.

An object of this invention is to provide a carburetor having highly improved means for increasing the supply of air to the mixing chamber simultaneously with the increase in the supply of fuel.

A further object of this inventon is to provide in a carburetor of the character described improved means for regulating the flow of air and fuel to the mixing chamber.

A still further object of this invention is to provide a compact and durable carburetor of the character described, comprising comparatively few and simple parts, which shall be relatively inexpensive to manufacture, smooth and positive in action and withal practical and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawing, in which is shown one of the various possible illustrative embodiments of this invention,

Fig. 1 is an elevational view of the carburetor embodying the invention with parts broken away to show the interior construction;

Fig. 2 is a top plan view of the carburetor shown in Fig. 1, with parts broken away to show the interior construction;

Fig. 3 is an enlarged detail fragmentary view of a portion of the carburetor shown in Fig. 1; and

Fig. 4 is a cross-sectional view taken on line 4—4 of Fig. 1, on a reduced scale.

Referring now in detail to the drawing, 10 designates a carburetor embodying the invention and comprises a float chamber 11 preferably cylindrical in shape and having a bottom wall 12 formed with a downwardly extending nipple 12a.

Extending from one side of the chamber 11 and adjacent the bottom wall 12 is a tube 13. Screwed to said nipple 12a is a fitting 14 in the form of a tube having a screw threaded bottom end closed by a screw threaded plug 15 having a shoulder 16. Said fitting 14 also includes a tubular portion 17 extending at an angle and adapted to be attached to the gasoline supply tank. The nipple 12a for the purpose hereinafter appearing, is formed with an inner conical or tapered opening 19. The top of the chamber 11 may be closed by a

cover 20 fixed thereto and having a central upwardly extending tubular projection 21 closed at the upper end. The stem 24 is slidably mounted within the tubular opening 25 of the tubular portion 21 and extends axially of the chamber 11 and is formed with a conical head 26 at the bottom thereof adapted to contact the conical surface 19. Attached to the stem 24 near the top thereof is a transverse pin 27. Slidably received on said stem is a floating member 28 of usual construction and made of cork or the like material and of hollow construction.

It will now be understood that gasoline passing through the tube 17 and through the fitting 14 may normally pass upwardly through the opening 19 into the float chamber. However, should the level of the gasoline within the chamber 11 rise beyond a predetermined point the floating member 28 will rise and by engagement with the transverse pin 27 will cause the stem 24 to be slidably moved upwardly, the lower conical end 26 thereof thus closing the conical or tapered opening and shutting off the supply of gasoline. When the quantity of gasoline within the chamber diminishes the floating member 28 will drop to permit the stem 24 to likewise be lowered for opening the passage 19.

Extending from the tube 13 is a portion 30 having a flat upper surface 31, and formed with a through screw threaded opening 32 communicating with the passage 13a in the tube 13, and extending at right angles thereto. Screwed to the screw threaded opening 30 is a member 35 having a nut 36 at the bottom thereof and being formed with an internally screw threaded opening 38 at the upper end thereof, and with a through opening 40 communicating with the passage 13a in tube 13. Fixed to said member 30 is a casting or member 42 having a cylindrical portion 43, the bottom end of which rests on the surface 31 of the portion 30. Extending from the cylindrical portion 43, at right angles thereto, is another cylindrical portion 44 adjacent the juncture between said portion and the portion 43, is an outwardly tapering tubular portion 45 formed with a flange 46 and forming an outlet passage 45a adapted to communicate with the manifold of an engine. The upper end of the portion 43 is formed with a flattened wall 47 having a screw threaded opening 48. The member 42 may be attached to the portion 30 by bolted contacting flanges, or in any other suitable manner.

Screwed to the opening 48 is a cap 49 forming an end wall to portion 44. The cylindrical por-

tion 44 is further formed with a tubular open extension 50 substantially coaxial with the tubular portion 45 and diametrically disposed with respect thereto.

5   Mounted on the screw threaded member 35 and extending axially of the cylindrical portion 43 is a member 55 having a screw threaded nipple portion 56 at the bottom end thereof screwed to the internal screw threaded opening 38. Extending from the nipple is a nut portion 57, and extending from the nut portion is a tubular portion 58 having an enlarged head 60 at the upper end thereof. The portion 60 is formed with a flat upper surface 61 and a flat side surface 62 facing and disposed parallel to the cap 49. The tubular member 58 is formed with a central through passage 63 communicating with the opening 40, and passage 13a through the bottom end of the nipple 56. At the upper end thereof, the passage 63 is formed with a tapered opening or portion 64. The head 60 is formed with a passage 65 transverse to the passage 64 and communicating therewith. Said head is also formed with a tapered opening 67 coaxial with the passage 65 and communicating with the face 62 of said head. Fixed to the underside of the head 60 is a bracket 70 extending away from the cap 49 and having a stop or shoulder portion 72 at the outer end thereof.

10   Slidably mounted within the passage 65 is a needle valve stem 76 having a head 77 at the outer end thereof. A small coil compression spring 78 is interposed between the head 77 and the head 60 and normally serves to press the head 77 against the stop 72. When the head 77 contacts the stop 72, as shown in Fig. 1 of the drawing, the conical end 80 of the stem 76 is spaced from the conical opening 67 so that both the openings 61 and 64 are open to permit the gas from the carburetor to flow therethrough. The diameter of the passage 63 is preferably somewhat greater than the diameter of the valve stem 76 to permit fuel to pass around said stem to the opening 64, even when said valve stem is in closed position, as shown in Fig. 3 of the drawing.

15   Means is provided, however, to move the stem 76 into position for closing the opening 67. To this end, there is slidably mounted within the cylindrical portion 44 a cylindrical sleeve 82 contacting the inner surface of said cylindrical portion. The sleeve 82 is formed with a cut-out portion 83 adjacent the right end thereof, looking at Fig. 1, and another cut-out portion 86 on the bottom thereof. It will be noted that when the sleeve is pushed to the right, the passage or opening 45a will be closed except for a small portion 87 at the part uncovered by the cut-out portion 86, and a portion 88 uncovered by the cut-out portion 83. When the sleeve 82, however, is moved to the left to the position shown in Figs. 1 and 2 of the drawing, the passage 45a is substantially entirely uncovered. When the opening 45a is uncovered, a free flow of air and fuel may pass to the manifold, as will be more fully explained hereinafter.

20   For the purpose hereinafter appearing, the sleeve 82 is provided with a transverse pin 90, and the outer end of the cylindrical portion 44 is likewise provided with a transverse pin 91, substantially parallel to the pin 90. Said cylindrical portion is formed with a pair of diametrically disposed bearing openings 92 rotatably receiving said pin 91. Said pin 91 extends beyond one of the bearing openings to the exterior of said cylindrical portion. There is fixed to said pin 91

25   a crank arm 95 which may be attached to a foot pedal or hand operated lever accessible to an operator. The pin 91 is provided with a central collar 96 within the cylindrical portion 44 and extending from said collar are a pair of spaced crank arms 97 carrying a pivot 98 at the outer end thereof. A link 100 interconnects the pivot pin 92 with the transverse pin 90.

30   It will now be understood that oscillation of the arm 95 will cause a reciprocating movement of the sleeve 82. Normally the parts are in the position shown in Fig. 3 of the drawing with the arm 95 pulled back and the sleeve substantially closing the port 45a and pressing the valve stem 76 to close the opening 67. With the parts in this position, a small amount of gasoline may pass through the passage 63 and around the valve stem and out through the opening 64 so that the motor may run at low speed supplied by a mixture of fuel and air through the portions 87 and 88 of the port or opening 45a.

35   Air may be supplied to the cylindrical portion 44 by means of an elbow 105 fixed to the outer end 106 of said cylindrical portion 44 and having attached thereto a spaced hood 107. Fixed to the elbow 105 is a transverse pin 108 carrying a butterfly valve 109. On the outside of the elbow there is fixed to the pin 108 an arm 110 connected through suitable mechanism to a point where the operator may actuate the valve 109 which 40 serves as a choke. The hood 107 is, of course, spaced from the upper end of the elbow 105 to permit air to pass through the elbow and through the cylindrical portion 44 to the port 45a.

45   An additional supply of air may be admitted 35 when the valve 67 is open, through the tube 50. A transverse screen 51 is preferably attached within the tube 50 to prevent particles of dirt from entering the carburetor.

50   It will now be understood that, normally, with the parts as shown in Fig. 3 of the drawing, the sleeve 82 is in closed position and merely leaves a small portion of the outlet passage 45a open. Some air may pass through the elbow 105 and a small amount of fuel passing through the opening 64 supplies some mixture to the motor. When it is desired, however, to accelerate the motor, the arm 95 is pushed forward to retract the sleeve and uncover the port 45a. Simultaneously with this motion, the spring 78 pushes the valve 76 to the left to uncover the opening 67 and increase the supply of gasoline.

55   It will be understood that the sleeve 82 also closes the tube 50 when the outlet opening 45a is closed. When the sleeve is moved to the position shown in Figs. 1 and 2 the tube or air port 50 is uncovered to increase the supply of air. The supply of air is thus increased simultaneously with the opening of the valve 67 for the admission of an additional supply of fuel.

60   Gasified and expanded hydrocarbon fuel, for example, from a retort such as shown and described in my co-pending application, Serial No. 551,016, filed July 15th, 1931, may also be supplied, as illustrated in Figs. 1 and 4 of the drawing. To this end, a supply tube 120 carrying gasified hydrocarbon oil from a retort, may pass upwardly into the chamber 45a, said tube 120 being provided with a valve 121. Thus after the motor is started, the supply of gas may be shut off and a valve 124 in the tube 120 opened to feed the gasified hydrocarbon oil to the manifold.

65   The tube 120 is provided with an angular extension 114 axially disposed within the outlet opening 45a and provided with a valve pocket. 70 75

- Screwed to the outer end of the tubular portion 144 and closing said pocket, is a cap 122 provided with pin openings 123. The tube 114 is further formed with a valve seat at the inner end of said pocket. Covering an axial opening 117 for the passage of the gaseous hydrocarbon fuel, and seated on the valve seat is a small one-way check valve 118 comprising a pair of curved, parallel notched flanges interconnected by a short stem. 5
- 10 The valve 118 is maintained on said seat by means of a coil compression spring 119 interposed between said valve and the cap 122. It will now be understood that when the pressure in the manifold decreases, the valve member 118 will 15 be unseated and permit the gaseous fuel to pass through the notches in said member and through the pin opening 123 into the manifold.
- It will thus be seen that there is provided a device in which the several objects of this invention are achieved, and which is well adapted to meet the conditions of practical use. 20
- 25 As various possible embodiments might be made of the above invention, and as various changes might be made in the embodiment set forth, it is to be understood that all matter herein set forth or shown in the accompanying drawing is to be interpreted as illustrative and not in a limiting sense.
- Having thus described my invention, I claim 30 as new and desire to secure by Letters Patent:—
1. In a carburetor, a member having a cylindrical portion, a second cylindrical portion extending at right angles to said first cylindrical portion and having an outlet adapted to communicate with the manifold of an engine, a tubular fuel supply member extending within said first cylindrical portion and projecting into said second cylindrical portion, means for supplying fuel to said tubular member, said tubular member having an axial opening, a valve stem slidably mounted on said tubular member and disposed at right angles to and crossing said axial opening, a sleeve slidably mounted within and engaging the inner surface of said second cylindrical portion and adapted to control said outlet, and means for causing sliding movement of said sleeve and said valve stem. 35
2. In a carburetor, a member having a cylindrical portion, a second cylindrical portion extending at right angles to said first cylindrical portion and having an outlet adapted to communicate with the manifold of an engine, a tubular fuel supply member extending within said first cylindrical portion and projecting into said second cylindrical portion, said tubular member having an axial opening, a valve stem slidably mounted on said tubular member and disposed at right angles to and crossing said axial opening, a sleeve slidably mounted within and engaging the inner surface of said second cylindrical portion for closing said outlet, means for causing sliding movement of said sleeve and valve stem, said second cylindrical portion being formed with an air port, said sleeve being adapted to close said air port and being movable to a position for opening said air port. 45
3. In a carburetor, a member having a cylindrical portion, a second cylindrical portion extending at right angles to said first cylindrical portion and having an outlet adapted to communicate with the manifold of an engine, a tubular fuel supply member extending within said first cylindrical portion and projecting into said second cylindrical portion, said tubular member having an axial opening, a valve 40
- stem slidably mounted on said tubular member and disposed at right angles to and crossing said axial opening, a sleeve slidably mounted within and engaging the inner surface of said second cylindrical portion, means for causing sliding movement of said sleeve and valve stem, said second cylindrical portion being formed with an air port and with an outlet passage adapted to communicate with said manifold, and said sleeve being adapted to be moved into overlapping relation with respect to said passage and air port. 10
4. In combination, a cylindrical member, an outlet passage communicating with said member, a tube extending into said member for feeding fuel thereto, a valve stem slidably mounted on said tube, a sleeve slidably mounted within said cylindrical member and contacting the inner surface thereof, said sleeve being movable into overlapping relation with respect to said outlet passage, a transverse pin mounted on said sleeve, a transverse pin on said cylindrical member parallel to said first transverse pin, said second pin extending to the exterior of said cylindrical member, an arm fixed to the extending portion of said second pin, an arm fixed to a portion of said second pin within said cylindrical member, a link interconnecting the outer end of said second arm with said first pin, said sleeve having a part thereon adapted to contact said valve stem. 15
5. In combination, a cylindrical member, an outlet passage communicating with said member, said member being formed with an air port, a tube extending into said member for feeding fuel thereto, a valve stem slidably mounted on said tube, a sleeve slidably mounted within said cylindrical member and contacting the inner surface thereof, said sleeve being movable into overlapping relation with respect to said outlet passage and air port, a transverse pin mounted on said sleeve, a transverse pin on said cylindrical member parallel to said first transverse pin, said second pin extending to the exterior of said cylindrical member, an arm fixed to the extending portion of said second pin, an arm fixed to a portion of said second pin within said cylindrical member, a link interconnecting the outer end of said second arm with said first pin, said sleeve having a part thereon adapted to contact said valve stem. 20
6. In a carburetor, a chamber, a tubular member extending within said chamber, means for supplying fuel to said tubular member, said tubular member having an outlet opening for normally supplying a small amount of fuel to said chamber, said tubular member having a second opening, a valve stem slidably mounted on said tubular member and disposed at right angles to said tubular member, and adapted to close said second opening, means for holding said stem in closing position, and spring means for moving said valve stem to uncover said second opening upon releasing said stem. 25
7. In a carburetor, a chamber, a tubular member extending within said chamber, means for supplying fuel to said tubular member, said tubular member having an outlet opening for normally supplying a small amount of fuel to said chamber, said tubular member having a second opening, a valve stem slidably mounted on said tubular member and adapted to close said second opening, means for holding said stem in closing position, spring means for moving said valve stem to uncover said second opening upon releasing said stem, said chamber being provided with an outlet passage adapted to be connected to the 30
- 75

manifold of an engine, and means associated with said holding means for controlling said outlet passage.

8. In a carburetor, a chamber, a tubular member extending within said chamber, means for supplying fuel to said tubular member, said tubular member having an outlet opening for normally supplying a small amount of fuel to said chamber, said tubular member having a second opening, a valve stem slidably mounted on said tubular member and adapted to close said second opening, means for holding said stem in closing position, spring means for uncovering said second opening upon releasing said stem, said chamber being provided with an outlet passage adapted to be connected to the manifold of an engine, and means associated with said holding means for controlling said outlet passage, said chamber being provided with an air port and said holding means being adapted to control said air port.
9. In a carburetor a cylindrical member having an outlet opening adapted to communicate with the manifold of an engine, means for sup-

plying fuel to said member, comprising a tubular member projecting therein and a float chamber connected to said tubular member, said tubular member having an opening, a spring pressed valve controlling said last-mentioned opening, a sleeve slidably mounted within said cylindrical member, means for moving said sleeve to overlapping position with respect to said outlet opening and means associated with said sleeve for moving said valve against the pressure of its spring, said valve being normally held in open position by said spring when said sleeve uncovers said outlet opening, and said sleeve being adapted to move said valve to closing position when said sleeve is moved to a position covering said outlet opening, said cylindrical member being provided with an air port aligned with said outlet opening and likewise being controlled by said sleeve, a passage having a hood at the end thereof and communicating with said cylindrical member and manual means for controlling the supply of air from said passage.

CHARLES A. ROSIER.
